UNITED STATES PATENT OFFICE.

PHINEAS H. ADAMS, JR., AND ORSEMAS T. X. ADAMS, OF CHICAGO, ILLINOIS,
ASSIGNORS TO MELINDA PECK, OF SAME PLACE.

APPARATUS FOR USE IN DECOMPOSING METALLIC SALTS AND DESULPHURIZING ORES.

SPECIFICATION forming part of Letters Patent No. 399,116, dated March 5, 1889.

Application filed January 3, 1889. Serial No. 295,362. (No model.)

To all whom it may concern:

Be it known that we, PHINEAS H. ADAMS, Jr., and ORSEMAS T. X. ADAMS, citizens of the United States, residing at Chicago, Illinois, 5 have invented certain new and useful Improvements in Apparatus for Use in Decomposing Metallic Salts and Desulphurizing Ores, of which the following is a specification.

The object of our invention is to improve 10 an apparatus for mechanically decomposing chemical compounds, metallic salts, and desulphurizing ores or their resulting material, when the substances treated are in a molten condition, by the action of centrifugal force, 15 and our invention has more particular reference to the running-gear employed in such apparatus.

In the drawings, Figure 1 is a vertical section of the apparatus, showing some of the 20 running-gear in elevation. Fig. 2 is a plan view of the apparatus, taken on line 22 of Fig. 1, and Fig. 3 is a vertical section of a modified form of bearing for the actuating-shaft.

In making our improved apparatus for decomposing chemical compounds, metallic salts, or salts of metal, and desulphurizing ores, we make a receiving - vessel, V, constructed and adapted to receive the substance to be treated when in a molten condition. 25

This receiving-vessel is mounted and rests upon an actuating-shaft, to which it is fixed or keyed in such a way that by the rotation of the shaft the receiving-vessel will be revolved. The receiving-vessel may be made in 30 such way as will secure the required strength and reduce the conduction of heat from the interior to the exterior. It may be surrounded by curbing and have a removable bottom to facilitate the removal of the material which 35

is not thrown off at the top by the action of centrifugal force; and in other respects it may be made as will be calculated to subserve the end in view, and permit of its being rotated at a high rate of speed for the separation 40

of particles of different degrees of density in the matter treated. Many of these parts and the details of their construction, as they do not form the subject-matter of our present claims, need not be more fully described, as 45

they will be sufficiently understood from an inspection of the drawings.

The actuating-shaft A, by which the receiving-vessel is rotated, is preferably made in one piece, instead of being divided into rigid and flexible portions. The upper part, 55 however, is preferably provided with a laterally-yieldable journal, B, to help maintain it in a vertical position. The lower portion of the actuating-shaft preferably rotates in a flexible journal, C, which we have shown, for 60 convenience and not from necessity, as a ball. This ball is preferably surrounded by a box or support, D, containing a lining of a size and shape to fit around the ball C and afford it the proper yieldable support. As shown in 65 the drawings, the lining is made of a separate piece from the box, but as to this matter we do not regard it as very material how the lining of the box is made, so long as it permits the flexible journal sufficient play to accommodate the vibrations of the shaft. 70

It is obvious that the ball form for the flexible journal shown in the drawings need not be closely followed, as the object is simply to provide a suitable flexible journal. It 75 may therefore be made as a wheel or disk at its outer edge so long as the support which it receives from contact with the interior of the box supports the shaft as nearly as possible in a vertical position while accommodating 80 its lateral vibrations as it is revolved at a high rate of speed, under the weight and influence of the receiving-vessel and its superimposed load. The lower end of the actuating-shaft is provided with or terminates in a 85 disk or head, E, which rotates with it and preferably forms its end. Immediately under this disk are arranged a number of balls or rollers, F, which rest in and are supported on a hardened surface in a bed or block, G, preferably screwed into a surrounding frame or box, G', depending from the journal C and vibrating in unison or conforming in its vibrations or movements to the vibrations or movements of such journal. This bed or 90 block is shown in the drawings as vertically adjustable in the box G', and we prefer to make it in this way, though we do not confine ourselves to such construction. Immediately under the bed or block G is preferably arranged a short supporting center or stud, H, whose ends are preferably oval or 100

rounded in form. The lower side of the bed or block G rests upon the upper end of this stud, and its lower end rests on the top of a block, I. This block I is preferably adjustable up and down by means of screw-threads, which enable it to be connected with the yoke J, which preferably depends from the base-plate K; but as it does not vibrate, like the bed or block G, we term it a stationary bed. 5 This yoke J when used therefore receives and sustains the weight of the shaft and its superimposed load. It is obvious, however, that the block I may be supported in any convenient manner. 10 In Fig. 3 we have shown a modification of the balls or rollers F and their manner of arrangement. In this figure we have shown sets of rollers or balls, with a rotatable block or plate, I, interposed between them. In 15 this case the bottom of the disk E and the bottom and top of the interposed block or plate are preferably cut out or shaped to receive and retain the rollers, as is also the block G. This will be readily understood by an inspection of Fig. 3, and need not be further described in detail, except that we wish to say that we prefer to use two or more sets of these rollers, so as to divide the very great friction caused by the rapid rotation of the actuating- 20 shaft with its superimposed load. 25

As a further means of maintaining the actuating-shaft in its plumb or vertical position against the lateral strain caused by the belt from the power-shaft M, which must necessarily be great in order to revolve the actuating-shaft with its heavy load, we prefer to employ one or more counter-shafts, N. In the drawings we have shown two such shafts, although it is obvious that a greater number 30 could be used, or only one directly opposite the power-shaft. We do not therefore desire to limit ourselves to any particular number of counter-shafts. These counter-shafts are provided with belt-surfaces which enable them 35 to be connected by belts with the actuating-shaft in such manner as to draw against the actuating-shaft in opposition to the power-shaft, and to support the shaft against the strain in a lateral direction caused by the belt 40 from the power-shaft. In this way we are enabled to largely counteract or counterbalance such strain and prevent the actuating-shaft from being drawn injuriously to one side. 45

50 55 What we regard as new, and desire to secure by Letters Patent, is—

1. In an apparatus for decomposing metallic salts or salts of metals and desulphurizing ores when in a molten state, the combination of a revoluble receiving-vessel adapted to receive molten material to be treated, a revoluble actuating-shaft rotating said vessel as it revolves, a flexible journal for the lower portion of the actuating-shaft conforming to the lateral vibrations of the actuating-shaft, a vibratable bed supporting the weight of the actuating-shaft and its superimposed load, 60

70 balls or rollers interposed between the rotating head of the actuating-shaft and their non-rotating vibratable bed, and means for rotating the actuating-shaft, substantially as described. 75

2. In an apparatus for decomposing metallic salts or salts of metals and desulphurizing ores when in a molten state, the combination of a revoluble receiving-vessel adapted to receive molten material to be treated, a revoluble actuating-shaft rotating said vessel as it revolves, a flexible journal for the lower portion of the actuating-shaft conforming to the lateral vibrations of the shaft, a vibratable bed supporting the weight of the actuating-shaft and its superimposed load and vibrating in unison with the vibrations of the flexible journal, balls or rollers interposed 80 between the rotating head of the actuating-shaft and their non-rotating vibratable bed, and means for rotating the actuating-shaft, substantially as described. 85

90 2. In an apparatus for decomposing metallic salts, or salts of metals, and desulphurizing ores when in a molten state, the combination of a revoluble receiving-vessel adapted to receive molten material to be treated, a revoluble actuating-shaft rotating said vessel as it 95 revolves, a flexible journal for the lower portion of the actuating-shaft conforming to the lateral vibrations of the shaft, a vertically-adjustable vibratable bed supporting the weight of the actuating-shaft and its superimposed 100 load and vibrating in unison with the vibrations of the flexible journal, balls or rollers interposed between the rotating head of the actuating-shaft and their non-rotating vibratable bed, and means for rotating the actuating- 105 shaft, substantially as described. 110

4. In an apparatus for decomposing metallic salts or salts of metals and desulphurizing ores when in a molten state, the combination of a revoluble receiving-vessel adapted to receive molten material to be treated, a revoluble actuating-shaft rotating said vessel as it revolves, a flexible journal for the lower portion of the actuating-shaft conforming to the lateral vibrations of the shaft, a box or frame 115 depending from the flexible journal and vibrating in unison therewith, a vibratable bed in the lower end of such box or frame supporting the weight of the actuating-shaft and its superimposed load, balls or rollers interposed between the rotating head of the actuating-shaft and their non-rotating vibratable bed, and means for rotating the actuating- 120 shaft, substantially as described. 125

5. In an apparatus for decomposing metallic salts or salts of metals and desulphurizing ores when in a molten state, the combination of a revoluble receiving-vessel adapted to receive molten material to be treated, a revoluble actuating-shaft rotating said vessel as it 130 revolves, a flexible journal for the lower portion of the actuating-shaft conforming to the lateral vibrations of the shaft, a vibratable bed supporting the weight of the actuating- 135

shaft and its superimposed load and vibrating in unison with the vibrations of the flexible journal, balls or rollers interposed between the rotating head of the actuating-shaft and 5 their non-rotating vibratable bed, a center or stud arranged beneath the vibratable bed, wholly or partially sustaining it, a stationary bed supporting the center or stud, and means for rotating the actuating-shaft, substantially 10 as described.

6. In an apparatus for decomposing metallic salts or salts of metals and desulphurizing ores when in a molten state, the combination 15 of a revolute receiving-vessel adapted to receive molten material to be treated, a revolute actuating-shaft rotating said vessel as it revolves, a flexible journal for the lower portion of the actuating-shaft conforming to the lateral vibrations of the shaft, a vibratable 20 bed supporting the weight of the actuating-shaft and its superimposed load and vibrating in unison with the vibrations of the flexible journal, balls or rollers interposed between the rotating head of the actuating-shaft and 25 their non-rotating vibratable bed, a center or stud arranged beneath the vibratable bed, wholly or partially sustaining it, a stationary vertically-adjustable bed supporting the center or stud, and means for rotating the actuating-shaft, substantially as described.

7. In an apparatus for decomposing metallic salts or salts of metals and desulphurizing ores when in a molten state, the combination 35 of a revolute receiving-vessel adapted to receive molten material to be treated, a revolute actuating-shaft rotating said vessel as it revolves, a flexible journal for the lower portion of the actuating-shaft conforming to the lateral vibrations of the actuating-shaft, a vibratable 40 bed supporting the weight of the actuating-shaft and its superimposed load, sets of balls or rollers interposed between the rotating head of the actuating-shaft and their non-rotating vibratable bed, with a rotatable 45 block interposed between the sets of balls or rollers, and means for rotating the actuating-shaft, substantially as described.

8. In an apparatus for decomposing metallic salts or salts of metals and desulphurizing 50 ores when in a molten state, the combination

of a revolute receiving-vessel adapted to receive molten material to be treated, a revolute actuating-shaft rotating said vessel as it revolves, a divided bearing for the lower end of the actuating-shaft comprising sets of balls 55 or rollers interposed between the rotating head of the actuating-shaft and their non-rotating bed, with a loose rotatable block interposed between the sets of balls or rollers, and means for rotating the actuating-shaft, substantially 60 as described.

9. In an apparatus for decomposing metallic salts or salts of metals and desulphurizing ores when in a molten state, the combination 65 of a revolute receiving-vessel adapted to receive molten material to be treated, a revolute actuating-shaft rotating said vessel as it revolves, a vibratable bed supporting the weight of the actuating-shaft and its superimposed load, a divided bearing for the lower 70 end of the actuating-shaft comprising sets of balls or rollers interposed between the rotating head of the actuating-shaft and their non-rotating bed, with a rotatable block interposed between the sets of balls or rollers, and 75 means for rotating the actuating-shaft, substantially as described.

10. In an apparatus for decomposing metallic salts or salts of metals and desulphurizing ores when in a molten state, the combination 80 of a revolute receiving-vessel adapted to receive molten material to be treated, a revolute actuating-shaft rotating said vessel as it revolves, a divided bearing for the lower end of the actuating-shaft comprising sets of balls 85 or rollers interposed between the rotating head of the actuating-shaft and their non-rotating bed, with a rotatable block interposed between the sets of balls or rollers, a power-shaft and one or more counter-shafts whose 90 belts connect with the actuating-shaft and draw against it from different lateral directions, and means for rotating the actuating-shaft, substantially as described.
